PLANE FILE SHOE ATTACHMENT

James G. Bennett, North Bend, Wash.

Application May 6, 1950, Serial No. 160,521

2 Claims. (Cl. 29—78)

1

This invention relates to a plane file shoe and file attachment and has for an object to provide an improved attachment for a hand or power plane which acts as a shoe or guard for protecting the surface of the plane and the blade when it is stored away and also to provide a file means for smoothing off a surface that has been planed and is particularly useful in smoothing or rounding off edges of the same material that has been planed.

A further object of this invention is to provide a file and guard attachment for a power or hand plane which may be snapped on to the plane and when so snapped on, the plane acts as a handle for manipulating the file attachment in a sanding or filing action providing the necessary body or weight thereto and where in the upturned sides of the attachment provide a finger cooperating serrated gripping surface when the bottom surface is used for filing and wherein either side surface may individually be used for filing at the same time with or independently of the filing action of the bottom surface.

A further object of this invention is to provide a file attachment for a plane wherein when so attached, the plane acts as a handle and the file attachment provides bottom and side filing surfaces which may be particularly useful in filing or smoothing two inside right angular surfaces as the inside of a drawer.

A further object of this invention is to provide a snap-on sander and file shoe for a hand or power plane.

A further object of this invention is to provide a snap-on shoe for a plane, which shoe is provided with a filing surface both on the bottom and side edges thereof.

A further object of this invention is to provide a file or guard shoe for a plane which in its most convenient form may be made to snap on but obviously may be attached by any other conventional means, such as bolts or the like.

A further object of this invention is to provide a sander shoe for a plane which shoe may be made of suitable material, such as cast or pressed steel properly tempered so as to provide a good filing, cutting, or sanding surface.

With the foregoing and other objects in view, as will hereinafter become apparent, this invention provides a construction, combination and arrangement of parts hereinafter set forth, claimed and disclosed in the accompanying drawing, wherein

Figure 1 is a side view of a plane to which the snap-on file shoe has been attached, ends of the side of the shoe being broken away;

2

Figure 2 is a perspective view of the snap-on file shoe of this invention;

Figure 3 is an end view of Figure 2; and

Figure 4 is a bottom plan of view of the file shoe.

There is shown at 10 the snap-on file shoe of this invention. This file shoe as disclosed in Fig. 1 is intended to be suitably and temporarily attached to a conventional plane, whether a hand plane or power plane. For purposes of illustration, the file shoe 10 of this invention is shown as temporarily attached to a hand plane 11 provided with its usual plane knife 12 on the knife support 13 and the usual knife adjusting stud 14 and also the usual knife locking stud 15 and knife holder 16, the other end of the blade 12 being extendable and retractable through the plane bottom 17, the bottom 17 extending up as the conventional plane sides 18. The steel file shoe 10 of this invention consists of a bottom wall 20 of a length and width just slightly greater than the length and width of the plane bottom 17. The side walls 21 extend upwardly along the long side edges of the bottom wall 20 and are internally spaced apart a distance at least equal to the distance between the outer surfaces of the plane sides 18.

The side walls 21 may be bevelled as at 22 near their ends. The bottom wall 20 is substantially rectangular and is provided with centrally located integral securing fingers 23 and 24 of a size and shape to extend over the ends of the plane bottom 17. As will be seen, one securing finger 23 is a snap finger which curves inwardly and then outwardly at 25 and have been treated so as to be resilient. The other securing finger 24 is an inturned hook arranged to receive one end of the plane bottom 17 thereunder. The distance between the out curved end 25 of the snap finger 23 and the inside of hook finger 24 is greater than the length of the plane bottom 17, the distance between the incurved surfaces of finger 23 inside of hook 24 is somewhat less than the length of the plane bottom 17. As a result, the shoe 10 may be attached to the plane 11, after the stud 14 has been actuated to retract the knife blade from extending through the plane bottom 17, by merely setting the plane 11 down into the shoe 10 between the side walls 21 and under hook finger 24 and pressing downwardly causing the spring finger 23 to move outwardly and then snap back over the end of the plane bottom 17, thus firmly, yet separably, attaching the shoe 10 to the plane 11. Of course, the shoe 10 will be made in appropriate sizes to fit conventional size existing hand or power planes.

The bottom and outer surfaces of the shoe bottom wall 20 and side walls 21 are provided with a serrated sander or file surface 26 and 27, the bottom surface 26 connecting with both side surfaces 27 by smoothly rounded edges 28 around which the serrations continue. These serrations 27 and 28 thus provide a file surface of any desired degree of fineness or coarseness and will be serrated or cut in a manner similar to any conventional hand file.

In operation, the sander shoe 10 is attached to the plane 11 in the manner above described. As so attached, the plane and attached shoe will be gripped and held in the hand in a very similar manner that the plane would be held by itself, the operator's fingers gripping either or both sides of the sander shoe at the same time. The operator then usually works the combined file shoe and plane over the surface of the material to smooth it by a filing action in the same manner that a piece of sandpaper attached to a block is used. By having an appropriate serrated surface on the sander shoe, the same smoothing action is provided as with fine or coarse sandpaper except for the benefit that the serrations are substantially permanent and do not wear away quickly as on a piece of sandpaper. Obviously, several shoes may be provided, each with a different type of serration so that any degree of coarseness or fineness may be available. The serrated surfaces extends on the rounded edges of the bottom and up the sides and either side may be used individually or simultaneously with the bottom. The rounded edge is useful so as to smooth or sand a molding regardless of how small it may be, while the ends of the bottom and sides are square so as to sand or smooth a surface close to an edge or an abutting wall.

While the preferred form of this invention has been shown and described, it will be understood that this invention is not restricted to the particular details of construction and arrangement hereinbefore set forth but that changes in such detail of construction may be made within the scope of what is hereinafter claimed.

Having thus set forth and disclosed the nature of this invention, what is claimed is:

1. A unitary file shoe attachment for a plane,

said file shoe attachment comprising a substantially rectangular metal sheet, upstanding side walls extending along the long edges of said substantially rectangular metal sheet, said side walls being integrally attached to said bottom wall by rounded edges, a serrated file surface cut into the bottom surface of said rectangular sheet, said serrated file surface extending about said integral rounded edge and up the outer surfaces of said side walls, and means for detachably attaching said shoe to a plane.

2. A unitary file shoe attachment for a plane, said file shoe attachment comprising a substantially rectangular metal sheet, upstanding side walls extending along the long edges of said substantially rectangular metal sheet, said side walls being integrally attached to said bottom wall by rounded edges, a serrated file surface cut into the bottom surface of said rectangular sheet, said serrated file surface extending about said integral rounded edge and up the outer surfaces of said side walls, and means for detachably attaching said shoe to a plane, said means being located at the short ends of said metal sheet and comprising an inturned hook finger on one of said short ends and a cooperating inwardly and outwardly flared curved snap finger at the other end.

JAMES G. BENNETT.
